UNITED STATES PATENT OFFICE.

SAVERIO CREAZZO, OF NEW YORK, N. Y.

DESIGN FOR A CIGARETTE AND MATCH DISPENSING RECEPTACLE.

Application filed November 18, 1922. Serial No. 4,326. Term of patent 7 years.

To all whom it may concern:

Be it known that I, SAVERIO CREAZZO, a subject of the King of Italy, residing at New York, in the county of New York and State of New York, have invented a new, original, and ornamental Design for Cigarette and Match Dispensing Receptacle, of which the following is a specification, reference being had to the accompanying drawing, forming part thereof.

The figure is a view in perspective of a cigarette and match dispensing receptacle, showing my new design.

I claim:

The ornamental design for a cigarette and match dispensing receptacle, as shown.

SAVERIO CREAZZO.
